2,375,621

CAN

Wilford E. Burns, Burlingame, Calif., assignor to
 M. J. B. Company, San Francisco, Calif., a
 corporation of Delaware

Application May 2, 1942, Serial No. 441,519

3 Claims. (Cl. 220—54)

This invention relates to improvements in tearing strip cans, and it has reference more particularly to metal cans of that kind having the tearing strip located within the outer layer of a triple layer collar that is formed as a part of and which encircles the can body, and wherein the removable end closure of the can is double seamed to a flange that continues from the top edge of the outer layer of the folded collar and is released for opening the can, by the removal of the tearing strip.

In cans of this kind, which heretofore have been made in accordance with the disclosures of my U. S. Patent No. 1,615,930, issued February 1, 1927, the opposite end portions of the metal blank which forms the cylindrical body of the can, are joined together in a soldered side seam of the lock and lap type. The locked portion of this seam extends from near the seaming flange at the lower end of the can body, to the lower edge of the triple layer collar at the top end. Beyond the lower end of the lock seam, the end portions of the blank are joined together in a lap joint, while beyond the top end, the parts are joined in a lap seam, with certain of the collar forming layers disposed in end to end relationship.

In the disclosures of the above mentioned patent, it has been explained and shown that the opposite ends of the body blank are so cut and notched at locations aligned with those parts to be embodied in the triple layer collar that after the folding of the blank to form the collar, and incident to the side seaming of the body, the tongue, which extends from one end of the tearing strip to receive the strip winding key, will overlap with the opposite end of the tearing strip at the outside of the body. Likewise, at the inside of the can, one end portion of the inner layer of the metal forming the folded collar will overlap with the other end portion but extends to the opposite side of the side seam than that to which the tearing strip extends. The end edges of the underlying layers of the collar abut each other in a joint that is angularly inclined relative to the side seam, the parts being held by the soldering of the side seam with the tongue left free for reception of the strip winding key thereto.

In carrying out the present invention, it is intended to employ substantially the same side seam joint in the can body as illustrated in the above patent, but without the employment of solder to hold the seam closed. Therefore, to make it a practical and satisfactory construction for the purposes to which the can is to be put,

it becomes necessary that some means be employed to attach or anchor that end of the outer layer of the folded collar from which the tongue extends, to the underlying layers in order that the joint will remain tightly closed, especially when an outward pull is applied to this portion by the initial winding of the strip onto the key. Furthermore, the anchoring of this corner is most desirable, in order to insure the integrity of the side seam at this particular location and to prevent the corner of the fold springing outward by reason of the natural tendency of the folded collar to straighten out, or due to the outward pull on the tearing strip.

It will be explained further that in some cans of this kind, using the soldered side seam, the outer layer or fold of the collar is formed with a short extension just below the tongue, but separated from the tongue, which is designed to overlap the joint and thus, when soldered, to tie together the ends of the outer layer of the folded collar across the side seam. This tie ordinarily holds the collar ends at the joint against outward springing at the side seam regardless of their tendency to do so because of the increased stiffness of the folded portion of the body blank.

In view of the foregoing, it has been the principal object of this invention to devise a practical and satisfactory means for the anchoring of the free end of the outer layer of the folded collar to the under layers thereof in order to insure a satisfactory joining of the parts in the side seaming operation, and to insure the holding of the seam against opening up incident to the outward pull of the tongue in the removal of the tearing strip from the collar.

More specifically stated, the objects of this invention reside in the provision of an anchoring tab for the outside end of the outer layer of the folded collar in a can of the kind described, and in the disposing and securing of this tab beneath the inner layers of the fold whereby to prevent any opening or springing of the joint or seam at this particular location.

Other objects of the invention reside in the details of the body blank, in the folding of the collar forming portion and in the manner of joining the ends of the blank to complete the side seam connection.

In accomplishing these and other objects of the invention, I have provided the improved details of construction, the preferred forms of which are illustrated in the accompanying drawing wherein—

Fig. 1 is a side view of a can embodying those

features of construction on which this invention is based.

Fig. 2 is an enlarged side view of a portion of the can, showing the side seam joint at the collar portion of the can, after the tearing strip has been partially removed.

Fig. 3 is an enlarged sectional view on the line 3—3 in Fig. 2, illustrating the function of the anchor tab and its disposition in the side seam joint.

Fig. 4 is a view of a part of the formed body blank prior to its being folded to form the triple layer collar, and prior to the joining of the ends of the blank to form the cylindrical body.

Fig. 5 is a similar view of the blank after it has been folded to form the collar band along one edge thereof.

Fig. 6 is an enlarged cross section on the line 6—6 in Fig. 1.

Fig. 7 is an enlarged view of a portion of the folded blank, showing the anchor tab after being clinched about the end edge of the two under layers of the fold.

Referring more in detail to the drawing—

1 designates the can body and 2 is the upper end closure secured thereto through the mediacy of the double seam designated at 3. Formed about the upper end portion of the body is a triple folded collar, comprising an outer layer 4, an intermediate layer 5, and the inside layer 6, which latter is a continuation of the main body blank. The upper edge of the outer layer of the folded collar extends beyond the top limits of the collar and is contained in the double seam 3; this flange being designated in Figs. 3 and 4 by reference numeral 3f.

Formed in the outer layer of the fold of the collar throughout its length and extending circumferentially of the body in the finished can, is the tearing strip 8, set off between parallel lines of scoring 9—9. One end of the strip extends beyond the side seam and forms a tongue 10 adapted to have a key applied thereto for the removal of the strip to detach the end closure. This tongue, as seen in Fig. 1, extends across and beyond the side seam, overlapping with the other end portion of the outer fold of the collar.

In Fig. 4, I have illustrated details of the cutting or formation of the can body blank. At the opposite end edges of the blank 11 are hook flanges 12 and 13, designed to be bent back to form hooks that can be interengaged to form the locked side seam 14. These flanges terminate short of the upper edge of the blank, and at the tongue end of the blank, just above the end of the flange 12 is a shallow, V-shaped notch defined by the notch edge portions 15 and 16. Immediately above this notch, and parallel to the tongue, is a short extension or anchor tab 18, and immediately above this is the tongue 10. Above the level of the tongue 10 is the flange 3f previously mentioned, which forms a part of the double seam whereby the closure is secured in place. The upper limit of the flange 13 is defined by a short slit 13' which, as seen in Fig. 4, is located at the same horizontal level as the upper end of the flange 12.

At the end of the body blank opposite that from which the tongue 10 extends, is a shallow V-shaped notch of the same dimensions as that first mentioned, but disposed close to the top edge of the body blank by the distance of half the width of the notch. This last notch is defined by the edges 20 and 21, and these edges are parallel respectively to the edges 16 and 15 of the first notch. The collar is folded while the blank is in the flat, by first folding the top edge portion

of the blank outwardly and downwardly along the dotted line 23 in Fig. 4. Then this downturned portion of the blank is folded upwardly at the line 24, and the folds flattened together. In the first folding operation, the edge 16 of the V-shaped notch will be caused to register with the edge 15, and likewise on the second folding, the edge 21 will register with edge 20, and the fold will be as shown in Fig. 5.

After the body blank has been formed and the collar portion has been folded, as in Fig. 5, the locking tab 18 is bent inwardly and clinched about the registered edges 15 and 16 and then beneath the adjacent edges of the two under layers of the fold so that it effects a holding connection as indicated in Figs. 2 and 3. At the time of clinching the tab 18, or subsequently thereto, the hook flanges 12 and 13 are bent back, one to the inside and one to the outside of the blank. In the folding of the flange 13 back upon the body material, a short tab 18x just above the slit 13' is left projecting, as seen in Fig. 5. Later the blank is bent about a forming horn into the cylindrical body form of the can, and these backturned flanges are engaged, interlocked and clamped together as is usual in the formation of the side seam of a can. The parts are so brought together at the side seam that the extending tongue 10 overlaps the outer side of the opposite end portion of the tearing strip, as illustrated in Fig. 1, and as indicated in dotted lines in Fig. 3. In this operation, the tab 18x is lapped across the seam as shown in Fig. 3. Thus, the clamping of the parts together to close the side seam effects a connection that is very substantial and secure.

With the above described manner of cutting the blank, folding the collar and joining the ends of the body blank in the side seam, the layers of metal forming the collar will assume the relative positions of Fig. 3, and the anchor tab 18 will effectively and securely retain the lower edge corner of the folded collar against any possible outward springing that would be incident to the outward pull therein that will be applied by the winding of a strip onto a key.

While this invention has been described in connection with a can having an unsoldered side seam, it is anticipated that this detail may be used in cans using a soldered side seam, or where other composition may be used to effectively close the seam when an airtight can is desired.

Having thus described my invention, what I claim as new therein and desire to secure by Letters Patent is:

1. A can of the character described having its body portion formed from a blank that has one edge portion thereof folded upon itself to form a triple layer collar about an end of the can body and there being a tearing strip set off in the outer layer of the folded collar, terminating at one end in a tongue that extends beyond the end edge of the collar at one end of the blank; said blank having its ends joined together, with the said tongue at one end of the collar overlapping the opposite end of the collar at the outside of the can, and there being an anchor tab extending from the end edge of the outer fold of the collar immediately below the tearing strip and clinched beneath the corresponding edge of an underlying layer of the folded collar.

2. A can of the character described having its body portion formed from a blank that has one edge portion thereof folded outwardly and downwardly against the blank, then the downturned portion folded outwardly and upwardly upon itself to form a triple layer collar about the out-

side of the can body; said blank being joined at its ends, with end portions of the inner and outer layers of the fold in overlapping relationship across the joint at inside and outside of the joint and with end edges of intermediate layers of the collar fold in end to end alinement; the outer layer of the fold having a tearing strip formed therein that terminates at one end of the collar in an extended tongue that overlaps the opposite end of the strip at the outside of the can, and an 10 anchor tab extending from the edge of the out-

side end of the outer layer of the fold, adjacent the lower corner of the fold and clinched about the corresponding edges of the underlying layers of the fold.

- 5 3. A can as recited in claim 2 wherein the clinched portion of said anchor tab is overlapped at the inside of the can wall by the end portion of the inner layer of the folded collar that extends across the joint of the abutting edges of the collar.
